UNITED STATES PATENT OFFICE

ALEXANDER F. JENKINS, OF BALTIMORE, MARYLAND

APPARATUS FOR MIXING GASES

Application filed October 11, 1929. Serial No. 399,006.

The present invention relates to gas mixing apparatus and particularly to apparatus for mixing rich and lean gases for the purpose of obtaining a mixed gas having a composition of such character that it is suitable for cutting and welding operations or the like.

Thus the invention contemplates the enrichment of gases such as ordinary city illuminating gas, coke-oven gas, or other by-product gases developed in industrial operations, with acetylene or other gas richer in heat units per unit of volume, the amount of the acetylene added to the lean gas being only sufficient to give the desired qualities to the resulting mixed gas. The resulting gas is less expensive, being composed generally of a large proportion of relatively inexpensive gas and a smaller proportion of relatively expensive gas, and furthermore is not so dangerous to handle or work with as the straight acetylene or other gas, being less explosive. It has also been found, that, by using a mixture of acetylene in some leaner gases the cutting of metals is materially facilitated, and, when the mixed gas is used for heating purposes, the heating of any given object can be more expeditiously accomplished. Furthermore, the mixed gas, does not case harden the metal as when acetylene or richer gases are used.

The invention may have various embodiments and in the accompanying drawings one such embodiment is illustrated by way of example.

In the drawings:

Figure 1 is a front elevation of a gas and air mixing device of the portable type, in which the essentials of the invention are embodied;

Figure 2 is a side elevation of the same;

Figure 3 is an axial section through a flow controlling valve shown in elevation in Figure 1;

Figure 4 is a transverse section through the same, and

Figure 5 is a top plan view of portion of the apparatus, partly broken away.

My improved mixing apparatus can be made as a stationary device or may be made

portable. For the great majority of uses portability is desirable and hence a portable apparatus is illustrated in the drawings and will be now described in detail. It will be realized however that where the apparatus is to be permanently installed upon a fixed base its appearance will be considerably altered, the essential elements of the combination however remaining the same.

In the drawings an elongated cylindrical tube is indicated at 10, this tube being closed at the top by cap 11 and at the bottom by cap 12 and being provided with three detachable legs 13 by means of which it is supported in a vertical position some distance above the ground or floor. The lowermost cap 12 is apertured to centrally receive a short pipe or coupling member 14 and clamped upon this member 14 is one end of a flexible conduit 15 by means of which the mixed gases under proper pressure are conducted away to the point of ultimate use, which may be for instance a cutting or welding torch.

The upper cap 11 is apertured to receive with a tight fit a vertical pipe 16 and through this pipe regulated quantities of two gases pass into the mixing chamber, in which chamber their intimate admixture is further facilitated. The mixing chamber also constitutes a reservoir, which tends to steady the flow from the discharge conduit.

The two gases to be intermixed are both fed into pipe 16 above cap 11 and to some extent this pipe serves as a mixing chamber prior to the delivery of the gases into the enlarged mixing chamber 10. The initial admixture of the two gases is effected within pipe 16 at about the point indicated at 17, pipe 16 being here provided with a branch 18. The upper end of conduit 16 is in communication with a source of gas supply, for instance, with a flexible conduit 19 which leads to an illuminating gas main or the like, this connection including, in the order named, a short conduit 20 which leads to a pressure regulating or reducing valve 21, which may be of the type shown in my Patent No. 1,603,112 issued October 12, 1926, a short vertically disposed conduit 22, a second

pressure reducing regulator 23 and a vertically disposed pipe or conduit member 24 to the lower end of which the flexible conduit 19 is attached. Branch pipe 18 is brought into communication with a flexible conduit 25 which may be connected to any suitable source of rich gas, such as acetylene, by a somewhat similar system of conduits and pressure reducing regulators. Thus pipe 18 is in communication with the outlet 10 port of the flow controlling valve 26 the inlet end of which is connected by a conduit 27 with the outlet of pressure regulator 28 and the inlet end of pressure regulator 28 being connected by a conduit 29 with the outlet of 15 the primary pressure regulator 30, which is directly connected by conduit 31 with the flexible conduit 25. Each of the pressure regulators above described is provided with a gauge by means of which the pressure of 20 the gas on the outlet side thereof can be observed, these gauges being indicated at 23', 21', 28' and 30' respectively.

The two primary pressure regulators 23 and 30 are individually adjustable by means 25 of the adjusting handles 23² and 30² respectively while the upper pair, or secondary pair, of regulators are interconnected so as to be simultaneously adjustable as well as 30 being individually adjustable.

Thus the adjusting stem of each upper regulator has threaded engagement with a cross bar 32, but no threaded engagement with the associated regulator shell, being 35 free to move axially therein.

Rotatably supported in this cross bar intermediate the regulators is an adjusting screw 33, which has threaded engagement with a member 34 secured to a transverse brace 35, the ends of which are welded or otherwise suitably secured to a circular guard ring 36, welded at one point to mixing chamber 10. Rotation of adjusting screw 33 therefore results in movement of cross bar 32 and simultaneous adjustment of regulators 40 21 and 28 to control the flow of gases therethrough respectively. Nevertheless, as will be apparent, the regulators 21 and 28 may be easily adjusted individually. I find this arrangement, permitting individual or simultaneous adjustment of the upper regulators, of great advantage in the operation 45 of the apparatus.

Check valves are indicated at 37 and 38, 50 these valves being provided to prevent one gas from backing up into the conduit through which the other gas is supplied for any appreciable supply.

The details of the flow controlling valve 55 26 are shown in Figures 3 and 4. This valve comprises a casing or valve body 40 which is cylindrical. One end is closed by a bottom cap 41 and the other end by a top cap 42 and coupling 43. Intermediate the ends of valve body is provided with a partition plate

44 having a series of ducts or small conduits 45 passing therethrough. The valve member is indicated at 46 and will be seen to comprise a disc like member having a portion of its circular margin cut away, as at 47. The valve is upon the end of a valve stem 48 which passes through the cap 42 and is provided with a handle 49 by means of which the valve may be rotated. The series of apertures or ducts 45 extend only around about one-third of the periphery of the division plate 44 and the cut away portion of valve 46 is of such length that, when the valve is turned to one position, all of these ducts or ports are uncovered. By rotating the valve in either direction from this position one or more of the ports may be closed. A pointer 50 which plays over a scale 51 indicates the position of the valve from the outside.

While I may support the various pressure regulators and other elements of the mechanism in any desired manner I prefer to support them upon the mixing chamber 10 and to this end I secured two or more transverse members 52 to the mixing chamber by any suitable means and the ends of these members are designed and constructed to receive and support, respectively, the pipe sections 24 and 31.

While the vertical pipes are thus firmly supported I prefer to also brace them transversely by the additional brace 53, the ends of which are attached to the circular guard ring 36, so that the whole structure is firmly tied together. The guard ring 36 serves to protect the gauges and regulators as well as to provide a support for the cross braces.

Under normal operating conditions, and after having once so adjusted the regulators that the proper mixture of gases is obtained, it is only necessary, to decrease or increase the flow, to manipulate the upper regulators, and the valve 26. For very large increases and decreases of flow all four of the regulators may be readjusted but ordinarily this is unnecessary. Of course, the regulators may be so manipulated, if desired, that one gas only flows to the mixing chamber and thence to the outlet conduit.

Having thus described the invention, what is claimed as new and desired to be secured by Letters Patent is:

1. A gas mixing unit comprising in combination, a mixing chamber, two conduits for gases of different properties leading to said chamber, an individually adjustable pressure regulator in each conduit, and an additional pressure regulator in each conduit, each such additional pressure regulator being individually adjustable and both additional regulators being interconnected for simultaneous adjustment, for the purpose set forth.

2. A gas mixing apparatus comprising in combination, a mixing chamber, two conduits for gases of different properties leading to

said chamber, an individually adjustable pressure regulator in each conduit, an additional pressure regulator in each conduit, each such additional pressure regulator being individually adjustable and both additional regulators being interconnected for simultaneous adjustment, and a valve in one of said conduits controlling the flow of gas therethrough, said valve being positioned intermediate the mixing chamber and one of said regulators.

3. A gas mixing apparatus comprising, in combination, a mixing chamber, two conduits for gases of different properties leading to said chamber, a pressure regulator connected with each conduit so as to control the pressure of the gas passing therethrough, each such regulator including a body and an adjusting screw, a member to which both adjusting screws are adjustably secured, and means for adjusting said member to effect the simultaneous movement of said adjusting screws.

4. A gas mixing apparatus comprising, in combination, a mixing chamber, two conduits for gases of different properties leading to said chamber, a pressure regulator connected with each conduit so as to control the pressure of the gas passing therethrough, each such regulator including a body and an adjusting screw, said adjusting screw projecting through an aperture in the wall of said body and being adapted to move freely through said aperture, a member with which both adjusting screws have threaded engagement, and means for adjusting said member to effect the simultaneous movement of said adjusting screws.

5. A gas mixing apparatus comprising, in combination, a mixing chamber, two conduits for gases of different properties leading to said chamber, a pressure regulator connected with each conduit so as to control the pressure of the gas passing therethrough, each such regulator including a body and an adjusting screw, said adjusting screws being disposed in parallel relationship, a member disposed transversely to both adjusting screws and having threaded engagement therewith so that said screws may be individually adjusted relatively to said member, and means for adjusting said member relatively to the regulator bodies, whereby the adjusting screws may be simultaneously adjusted.

In testimony whereof I hereunto affix my
55 signature.

ALEXANDER F. JENKINS.
